UNITED STATES PATENT OFFICE.

WILLIAM E. NEWNAM, OF COLLINSVILLE, ILLINOIS, ASSIGNOR TO NATIONAL LEAD COMPANY, OF JERSEY CITY, NEW JERSEY, A CORPORATION OF NEW JERSEY.

FURNACE-CHARGING METHOD.

Original application filed July 27, 1922, Serial No. 577,923. Divided and this application filed July 5, 1924. Serial No. 724,369.

To all whom it may concern:

Be it known that I, WILLIAM E. NEWNAM, a citizen of the United States, and residing at Collinsville, county of Madison, Illinois, have invented the new and useful Improvement in Furnace-Charging Methods, of which the following is a specification.

This invention relates to furnace charging methods, and more particularly to methods adapted for charging lead smelting furnaces. This application is a division of application Serial No. 577,923, filed July 27th, 1922.

Lead smelting furnaces are of elongated form and it is necessary to charge the same periodically with ore, fuel and flux in the proper proportions. As such furnaces must be kept in constant operation, not only is it necessary that the charging system be simple, but also efficient and reliable and at all times under control. The components of the charge should also be properly mixed in the furnace.

One of the objects of this invention, therefore, is to provide a method whereby the components will be properly assembled and deposited in the furnace.

Another object of this invention is to provide a method whereby the placement of the assembled charge in the furnace and the selection of components to make the charge is under control of the superintendent.

Further objects will appear from the detail description taken in connection with the accompanying drawings, in which:

Figure 1 is a plan of a system for carrying out this invention;

Figure 2 is an elevation;

Figure 3 is an end view taken from the left hand end of Figure 1; and

Figure 4 is a diagram illustrating the relation of the several parts.

The drawings are diagrammatical in form, and no attempt has been made to show details of construction, for as to these details, any suitable known mechanism may be used well known to those skilled in the art.

Referring to the accompanying drawing, and more particularly to Figures 1 and 2, arranged along a suitable track 12 are a series of bins 10, 11, etc., which receive components of the charge which may be dis-

tributed in these bins in any suitable manner, as by cars running on overhead tracks 13 and 14; where the plant is one for the smelting of lead, the bins are charged with ore, fuel and flux. Thus, for example, in Figure 1, the first three bins 10, 11 and 20 may contain coke, bins 21 and 30, grey slag, bins 31 and 40, dross, 41 and 50, grey slag, 51, gravel, 60, limestone and 61, iron cinder. The components of a charge can, however, be placed in the bins to suit the requirements or practice of the particular superintendent of the plant.

The track 12 runs in a sub-way 15 below the floor level of the bins and over this track extend a series of weighing devices 1, 2, 3, 4, 5 and 6 which, in the particular embodiment shown, are placed opposite alternate partitions of the bins. Each of these weighing devices has a pair of hoppers, each of which has a multiple beam 75 scale.

The track 12 extends underneath a sinter cake plant 16, such as the usual Dwight Lloyd apparatus, which is provided with outlet hoppers 17 and 18 discharging into 80 weighing devices 7 and 8 which may be similar to the weighing devices 1 to 6 inclusive.

The track 12 has a branch 19 on the same level and on which a gathering car 22 running on the track may be switched. This gathering car is arranged to run underneath the weighing devices 1 to 8 inclusive to receive the charge therein, as hereinafter described. Crossing the branch track 19 is an inclined track 23 which leads from a pit below the track 19 to the furnaces 24 and 25, and on this track is arranged to run a charge car 26. Accordingly the charge gathered by the gathering car from the several weighing devices is dumped into the charge car to a position therebelow, as shown in Figure 2. The charge car is then wheeled up the incline and over a selected furnace to dump the charge therein. For 100 this purpose, suitable cables may be provided or the cars may be operated electrically as is well known to those skilled in the art.

Referring now to Figure 4, the weighing device shown, as previously referred to, is 105 in duplicate and comprises a pair of weighing hoppers 27, each of which has a scale, not shown. This scale may be of the multi-

ple beam type having setting devices so that each hopper may have weighed therein successively from one to four or more different components of the charge. Such 5 multiple beam scales are well known in the art and a further description thereof is, therefore, unnecessary.

The arrangement of the hoppers and scales for the Dwight Lloyd apparatus is 10 similar to those previously described for the weighing devices 1 to 6 inclusive and the same parts are indicated by like reference characters.

The gathering car 22 is shown in outline 15 in Figure 4 and is divided by a transverse partition 44 to divide the hopper or body into two distinct compartments, one at each end corresponding respectively to the hoppers of a weighing device. This truck may 20 be electrically driven and may be provided with suitable dumping devices which may, however, be of any suitable construction well known to those skilled in the art, and a further description thereof is, therefore, un- 25 necessary.

The charge car 26 comprises a suitable hopper or body 47 which, as in the case of the gathering car, is of elongated form and is also divided by a transverse partition 48 30 to form two compartments, one at each end. The bottom of this charge car body is also of the drop type and any suitable dropping mechanism is provided which may be of any suitable construction well known to 35 those skilled in the art.

In the operation of the system embodying this invention, let us take, for example, that the device 1 is loaded with coke from either bin 10 or 11, device 3 is loaded with grey 40 slag and dross from bins 30 and 31, device 5 with grey slag from bin 50 and gravel from bin 51, and device 6 with limestone from bin 60 and iron cinder from bin 61. As the gathering car now passes underneath the 45 hoppers at the several assembling stations, the driver will successively dump the contents into the gathering car so that when the gathering car reaches the branch 19, it will be fully loaded with the components of 50 the charge successively dropped therein. As the gathering car is positioned over the charge car, the contents are dumped into the charge car and the latter is wheeled up the incline and the contents dumped into the 55 furnace.

It will be understood that in some cases a charge of the sinter cake from the Dwight Lloyd plant can be weighed into the charge car in a similar way, either alone or in connection with components of the materials 60 from the devices 1 to 6 inclusive. It will further be understood that a series of components may be placed in a single hopper as the multiple beam scale provides for ready 65 weighing of the same.

In the operation of the plant, no fixed rule need be followed as to the weighing hopper in which a given component is placed, as in practice this is governed almost entirely by the nearness of the weighing hopper to the storage bin; the idea being to place the components from any such storage bin in the nearest weighing hopper in order to reduce the length of haul from the storage bin to the weighing hopper. It is not necessary that the components be bedded even in the weighing hopper, as they can be placed at random therein by first drawing from the hopper of the lowest number containing the charge components and drawing successively from the other weighing hoppers containing the charge components. The main purpose of the arrangement of the storage bins and weighing hoppers is to shorten the haul from the storage bins to the weighing hoppers. Accordingly the same charge component can be stored in two or more storage bins, sometimes adjoining and sometimes remote from each other. By 75 employment of a series of weighing hoppers, when a charge component in one bin is exhausted, the same charge can be drawn from another bin located remotely from the exhausted bin and placed in the nearest weighing hopper, thus minimizing the haul from the storage bins to the weighing hoppers. While, therefore, the components of the charge are often placed in different hoppers, such components are successively picked up 80 as the gathering car passes underneath the same. This is not for the purpose of bedding the charge but for shortening the haul of any given component or components. As a matter of fact, one hopper will frequently 85 be loaded with two components which are not bedded even in the weighing hopper.

Upon referring to Figure 4, it will be noted that the length or horizontal extent of the different hoppers, cars and furnace increase progressively. Thus, for example, the weighing hoppers 27 have a combined length of eight feet, the gathering car 22 has a length of nine feet, the charge car 26 has a length of eleven feet, while the furnace 25 has an inside measurement of twelve feet, three inches. Thus, it will be seen that the increase in horizontal extent or length from the weighing hopper to the furnace is over fifty per cent. This is advantageous, for as the charge is successively dropped from the weighing hopper to the gathering car, to the charge car, and into the furnace, this charge is progressively extended or spread out, thereby resulting in a better distribution 100 and mixing of the charge. This mixing is finally accomplished in the furnace where the mixing is provided to cause the charge to spread outwardly toward the sides of the furnace as is required. This charge is, however, simply dropped from the weighing 105

hopper to the gathering car and the charge car.

As previously pointed out, the weighing devices have duplicate hoppers and these correspond to the compartments of the gathering car and the charge car. Accordingly the charge is kept in two separate or parallel bodies, one at each end. Accordingly the delivery of the charge to the furnace can be selectively controlled, for example, if it is desired to vary the charge from one end of the furnace with respect to the other, either in quantities or in components, this can be readily accomplished by varying the delivery of the components of the charge to the weighing hoppers. Thus, where only one weighing hopper of a set is loaded, one end of the gathering car will be loaded heavier than the other, and in the same way, the quality and the proportion of the ingredients in the separate ends can also be varied.

In a plant of this type, it is very essential that the plant be kept in continuous operation. Accordingly the mechanism, such as the gathering and charge cars should be in duplicate. In order to provide for the charge car being duplicated, a reserve car 260 is kept on an elevated track 52 which has a switch 53 suitably controlled by a counter-weight 54 and hoisting cables 55, so that this switch 53 may be dropped down on the main cross track 23. This allows the reserve car to replace the regular charge car.

While this system has been described as being particularly applicable to a lead smelting plant, it is obvious that many of its features are applicable to other plants, such as copper smelting plants which also use elongated furnaces. It is further obvious that various changes may be made in details without departing from the spirit of this invention; it is, therefore, to be understood that this invention is not to be limited to the specific details shown and described.

Having thus described the invention, what is claimed is:

1. In the art of charging elongated furnaces, the process comprising, weighing and assembling the components of a charge to form a body of the material, transferring the body and extending the same horizontally and depositing the extended body in the furnace.

2. In the art of charging elongated furnaces, the process comprising, weighing and assembling the components of a charge to form a body of the material, transferring the body and extending the same horizontally, depositing the body in the furnace and still further extending the same therein.

3. In the art of charging elongated furnaces, the process comprising, assembling the components of a charge to form parallel bodies of the material, and transferring the bodies while they are maintained separated.

4. In the art of charging elongated furnaces, the process comprising, assembling the components of a charge to form parallel bodies of the material, selectively transferring said bodies, and depositing the selected body in the furnace.

5. In the art of charging elongated furnaces, the process comprising, weighing and assembling the components of a charge to form separate parallel bodies of the material, transferring the separate bodies while they are maintained separated, and extending the bodies horizontally.

6. In the art of charging elongated furnaces, the process comprising, assembling the components of a charge to form separate parallel bodies of the material, selectively transferring the separate bodies and extending each body horizontally.

7. In the art of charging elongated furnaces, the process comprising, assembling the components of a charge at a station in order to form a body of the material, transferring the body and extending the same horizontally before depositing the charge in the furnace.

8. In the art of charging elongated furnaces, the process comprising, assembling the components of a charge at a series of stations, with one or more components assembled at each station, gathering the components from the several stations to form a charge, extending the gathered charge horizontally, and depositing the extended charge in the furnace.

9. In the art of charging elongated furnaces, the process comprising, assembling the components of a charge at a series of stations, with one or more components assembled at each station, gathering the components from the several stations, transferring the gathered charge and extending the same horizontally before depositing the charge in the furnace.

10. In the art of charging elongated furnaces, the process comprising, assembling the components of a charge at a series of stations, with one or more components assembled at each station, gathering the components from the several stations to form separate parallel charge bodies, transferring and extending the separate bodies, and depositing the gathered charge in the furnace.

In testimony whereof I affix my signature this 18th day of June, 1924.

WILLIAM E. NEWNAM.
